UNITED STATES PATENT OFFICE.

FRANKLIN GAGE BECK AND WILLIAM DOUGLAS SAUNDERS, OF ST. LOUIS, MISSOURI.

RAILWAY-GATE-ACTUATING APPARATUS.

Application filed October 9, 1920. Serial No. 415,745.

To all whom it may concern:

Be it known that we, FRANKLIN GAGE BECK and WILLIAM DOUGLAS SAUNDERS, citizens of the United States, and residents of 5 St. Louis and State of Missouri, have invented certain new and useful Improvements in Railway-Gate-Actuating Apparatus, of which the following is a specification.

Our invention relates to railway crossing 10 gates and more particularly to an apparatus for effecting the automatic opening and closing thereof.

The purpose of our invention is the provision of a crossing gate actuating apparatus 15 of simple and efficient construction which is operable by and upon the approach of a train or car to a railway crossing to close the gate and to open the gate only after the train has traversed and is clear of the crossing. 20

It is also a purpose of our invention to provide an apparatus of that character in which both audible and visible signals are automatically operated upon raising the 25 gate, and means for checking the closing of the gate when a vehicle or other obstacle is in its path when closing.

We will describe one form of crossing gate and one form of apparatus for actuating the 30 same embodying our invention and will then point out the novel features thereof in claims.

In the accompanying drawings:

Figure 1 is a view showing in side elevation one form of crossing gate embodying 35 our invention.

Figure 2 is an enlarged fragmentary sectional view of the gate and pedestal therefor showing a portion of the actuating apparatus embodying our invention. 40

Figure 3 is an enlarged fragmentary view of the end of the gate shown in the preceding views.

Figure 4 is a vertical sectional view of 45 the pedestal shown in Figure 2 and with a portion of the adjacent supporting means for the gate shown in section.

Similar reference characters refer to similar parts in each of the several views.

Referring specifically to the drawings, A 50 designates generally a crossing gate which is vertically movable to occupy closed and open position upon a shaft 15 journaled in a hollow pedestal P. The gate A consists 55 of a tapered beam 16 at the wider end of which is arranged counter-balancing weights

17. As shown in Figure 4, the beam 16 is arranged between a pair of collars 18 and 19 keyed to the shaft 15. The collar 19 is notched to normally receive a locking dog 60 or pawl D mounted within the beam 16 and biased to locking position by means of a spring 14, as clearly shown in Figure 2. The dog D is connected to one end of an operating cable C which is supported below 65 the beam 16 by means of brackets H. The opposite end of the cable C is fixed to the outer or smaller end of the beam 16 so that when lateral tension is exerted upon the cable C the dog D is moved out of engagement with the collar 19. 70

As the beam 16 is loosely fitted on the shaft 15 it will be clear that when the pawl is in engagement with the collar 19, rotation of the shaft effects a lowering or elevating 75 of the beam. However, when the dog is disengaged from the collar, the beam 16 is no longer operatively connected to the shaft 15 so that rotation of the latter is ineffective to lower or elevate the gate. As shown in 80 Figures 2 and 4, the pedestal P contains a portion of the gate actuating apparatus and completely houses such portion against the action of the elements. This part of the actuating mechanism consists of a gear 20 85 fixed to the shaft 15 and meshing with a rack 21 carried by or formed on the upper end of a movable core 22 of a solenoid M. The rack 21 is counter-balanced by a weight 23 connected to a cable 24 trained over pulleys 25 and connected to the upper end of the rack 21. 90

M' designates a releasing solenoid, the movable core 26 of which is pivotally connected to a link 27^a which latter in turn is 95 connected to an arm 27 formed on a yoke Y which is mounted for swinging movement about a pin 28 as a center. The lower arm of the yoke Y is disposed in the path of movement of a pin 29 formed on the rack 100 21, while the upper arm of the yoke is provided at its free end with a tapered tooth 30 which is adapted to engage a reversely tapered lug 31 secured to the rack 21. The yoke Y as a unit is normally biased to the 105 locking position shown in Figure 2 by means of a coiled expandible spring 32 mounted on a rod 33 pivotally connected to the yoke Y and slidable through a bracket 34. The spring 32 bears against a head 33^a formed 110 on one end of the rod 33 so as to normally bias the rod into engagement with the yoke

Y thereby causing the tooth 30 to occupy an engaging position with respect to the lug 31.

From the foregoing arrangement, it will be seen that when the solenoid M is energized a downward movement is imparted to the rack 21 while the latter being in mesh with the gear 20 effects the rotation of the shaft 15 to move the gate A from the vertical position to the horizontal position 10 shown in Figure 2. The downward movement of the rack 21 is practically unrestricted because the mounting of the yoke Y and the bevel surface of the lug 31 and the tooth 30 permits the free downward 15 passage of the pin 29 and the lug 31, it being understood that as soon as the lug 31 has passed the tooth 30, the spring 32 acting on the yoke Y moves the tooth back into the path of the lug so as to overlie the latter 20 in the manner shown in Figure 2 whereby, upward movement of the rack 21 is prevented. The locking of the rack 21 in this position prevents the counter-weight 17 from returning the gate to its normal vertical 25 position and thereby maintains the gate in closed position.

To effect a return of the gate to open position, the solenoid M is de-energized and the solenoid M' is energized thereby causing the 30 downward movement of the core 26 to effect a rocking movement of the yoke Y so as to cause the tooth 30 to disengage and move out of the path of the lug 31 thereby releasing the rack 21 so that the weights 17 are free 35 to move the gate to the vertical position. By the rocking of the yoke Y and the downward movement of the core 26, the lower arm of the yoke exerts a lifting action on the rack 21 through the pin 29 thereby imparting an initial impulse to the gate so that the 40 weights 27 can respond and effect a lifting of the gate.

Should a vehicle or other obstruction be disposed within the path of the gate as it is 45 moving to closed position, it will be clear that such vehicle or obstruction engages and thus exerts lateral pressure upon the cable C so as to throw the dog D out of engagement with the collar 19 and to thereby disconnect the gate from the shaft 15 so that the 50 movement of the rack bar 21 is ineffective to continue the movement of the gate to closed position. As soon as the gate becomes disconnected from the shaft 15, the 55 counterweights 17 function to return the gate to open position.

Although we have herein shown and described only one form of gate embodying our invention, it is to be understood that various 60 changes and modifications may be made

herein without departing from the spirit of the invention and the spirit and scope of the appended claims.

What we claim is:

1. A railway gate actuating apparatus comprising, a shaft, a gear fixed to the shaft, a rack bar meshing with the gear, electro-magnetically operated means for moving said rack bar in a direction to effect a lowering of the gate, a lug formed on the bar, a yoke fulcrumed adjacent the bar, a tooth formed on the yoke, means for biasing the yoke so as to cause the tooth to be disposed within the path of said lug, and electro-magnetically operated means for moving the yoke to cause 75 said tooth to be removed from the path of said lug.

2. A railway gate actuating apparatus comprising, means for moving the gate to closed position, a solenoid for actuating said 80 means, means for latching the first means, so as to maintain the gate in closed position, and a second solenoid for moving the latching means to releasing position, said latching means being associated with the first means 85 in a manner to impart an initial impulse thereto when the second solenoid is energized.

3. A railway gate actuating apparatus comprising, a shaft, a gear fixed to the shaft, 90 a rack bar meshing with the gear, a solenoid having the core thereof operatively connected to the bar, a lug formed on the bar, a yoke fulcrumed adjacent the bar, a tooth formed on the yoke, a spring pressed rod engageable with the yoke for normally maintaining the tooth in the path of said lug, and a solenoid operatively connected to the 95 yoke for moving the same to cause said tooth to be removed from the path of the lug.

4. A railway gate actuating apparatus comprising, a shaft, a gear loosely mounted on the shaft, a rack bar meshing with the gear, electro-magnetically operated means for moving the rack bar in a direction to effect a lowering of the gate, a lug formed on the bar, a yoke fulcrumed adjacent the bar, a tooth formed on the yoke, means for biasing the yoke so as to cause the tooth to be disposed within the path of the lug, electro-magnetically operated means for moving the yoke to cause the tooth to be removed from the path of the lug, a gate carried pawl biased to normally engage said gear, and a cable slidably supported at the lower edge 110 of the gate and connected to said pawl in such manner that when flexed laterally the pawl is moved to disengage said gear.

FRANKLIN GAGE BECK.

WILLIAM DOUGLAS SAUNDERS.
